UNITED STATES PATENT OFFICE.

JOHN CARRUTHERS AND EDWIN J. FITHIAN, OF GROVE CITY,
PENNSYLVANIA.

CLUTCH.

SPECIFICATION forming part of Letters Patent No. 682,128, dated September 3, 1901.

Application filed December 26, 1899. Serial No. 741,535. (No model.)

To all whom it may concern:

Be it known that we, JOHN CARRUTHERS and EDWIN J. FITHIAN, citizens of the United States, residing at Grove City, in the county 5 of Mercer and State of Pennsylvania, have invented certain new and useful Improvements in Clutches; and we do hereby declare the following to be a full, clear, and exact description of the invention, such as will enable others skilled in the art to which it appertains to make and use the same.

This invention relates to clutches; and it consists in certain improvements in the construction thereof, as will be hereinafter fully 15 described, and pointed out in the claims.

More particularly, our invention relates to that class of clutches shown and described in our Patent No. 641,370, granted January 16, 1900.

Figure 1 shows a section on the line 1 1 in Fig. 2. Fig. 2 shows an elevation from the top of Fig. 1, a part being broken away to better show construction.

A marks the shaft which in the construction shown carries the driving member B, which is locked against rotative movement on the shaft by the key a. This driving member comprises the hub or sleeve B, the web B², which extends outwardly from it, and the 25 flange B', the inner surface of which forms the friction-surface of the driving member.

The pulley C, which may be termed the "driven" member of the clutch, comprises the hub C', the web C², extending outwardly 35 from the inner end thereof, the flange C³, extending outwardly from the web C² over the hub C', the spokes c, extending from the outer end of the flange, and the rim C⁴, arranged on the spokes in the usual manner.

The friction-shoes D D are provided with the guides d, in which are grooves d³. (Shown in dotted lines.) These guides engage the guides c³, preferably carried by the spokes c of the pulley C. At the ends of the shoes are 40 arranged the nuts d'. Reversely-threaded screws E are arranged to operate in the nuts d'. The worm-gears F are secured on these screws. A worm G, carried by the sleeve G', is adapted to engage the worm-gear F. The 45 sleeve G' is journaled on the hub C' and is locked against axial movement thereon, but

is free to rotate on said hub. The gears F extend through slots c' in the flange C³, so that the inner edges of the gears protrude sufficiently to permit the engagement of the 55 worm G with the gears F.

A cap H is secured to the end of the hub B and extends outwardly therefrom, forming a flange, which holds the hub C' and the sleeve G' in place. On the inner edge of the plate 60 H are the detents h, which are adapted to engage the detents i of the hand-wheel I, so as to form a clutch by means of which the hand-wheel I is locked with the plate H, and hence with the driving member B. The hand-wheel 65 I is arranged on the sleeve G and is free to move axially thereon and is locked against rotative movement on the sleeve by a spline-and-groove mechanism i'.

The operation of the device is as follows: 70 When it is desired to set the clutch, the hand-wheel is drawn out, so as to set the auxiliary clutch formed by the detents h and i. This locks the sleeve G' with the driven member B and causes the worm G to rotate relatively 75 to the gears F. This creates a rotative movement of the gears F, and consequently a movement of the screws E, which separate the shoes D, bringing them into contact with the friction-surface on the flange B'. This outward movement of the shoe is continued so 80 long as there is relative movement between the driving and driven members, so that a sufficient pressure is created to set the clutch, and at the same time the parts are only 85 strained sufficiently to effect this result, because as soon as the members move together the setting action is stopped. To disengage the clutch, the hand-wheel is pushed in, throwing the auxiliary clutch out of engagement. 90 The hand-wheel is then subjected to a brake action which retards the hand-wheel and causes the sleeve G' to rotate relatively to the driving and driven members, and this, through the action of the worm G, gears F, 95 and screws E, draws the friction-shoes out of contact.

What we claim as new is—

1. In a friction-clutch, the combination with the driving and driven members; of a 100 friction device interposed between said members comprising friction-shoes arranged to

be moved into and out of operative engagement, by a movement in a radial direction; a worm arranged to actuate said shoes, said worm being journaled with the axis of the 5 driving member, as a center, and means actuated by the relative movement of the members, one to the other, for actuating said worm.

2. In a friction-clutch, the combination 10 with the driving and driven members; of a friction-shoe; a screw arranged to move said shoe into and out of engagement; a worm-gear secured to said screw; a worm arranged to mesh and actuate said gear, said worm 15 being journaled with the axis of the driving member as a center; means actuated by the relative movement of the members, one to the other, for actuating said worm.

3. In a friction-clutch, the combination of the driving member, B, having a web, B² and flange, B' thereon; the driven member comprising the hub, C', web, C², and flange, C³; the friction-shoe, D; the screw, E, for actuating said shoe; the gear, F; the worm, G; meshing said gear and journaled on the hub, 25 C', and means for throwing said worm into and out of engagement with the driving member, B.

In testimony whereof we affix our signatures in presence of two witnesses.

JOHN CARRUTHERS.
EDWIN J. FITHIAN.
